UNITED STATES PATENT OFFICE.

FREDERICK JOHN TREVALLON BARNES, OF BRISBANE, QUEENSLAND, AUSTRALIA.

MEANS FOR STARTING INTERNAL-COMBUSTION MOTORS OR ENGINES.

1,114,334.

Specification of Letters Patent. Patented Oct. 20, 1914.

Application filed January 10, 1914. Serial No. 811,412.

To all whom it may concern:

Be it known that I, FREDERICK JOHN TREVALLON BARNES, a subject of the King of Great Britain, residing at Brisbane, 5 Queensland, Australia, have invented certain new and useful Improvements in Means for Starting Internal-Combustion Motors or Engines; and I do hereby declare the following to be a full, clear, and exact description of the invention, such as will enable others skilled in the art to which it appertains to make and use the same.

My invention relates to improved means for starting such types of motors as require 15 to be rotated until they start to develop their own power; and while not confined to such it is especially applicable to motor-driven vehicles enabling the driver to start the motor without any appreciable effort, and 20 without leaving the driving seat. The description applies particularly to motor cars merely to illustrate—the device is equally applicable to marine or other motors. I am aware that numerous devices exist for 25 attaining this end, such as:—mechanical contrivances for cranking up operated by a lever from the driver's seat. Compressed air from a receiver admitted to one or more cylinders of the motor, the air being supplied by a small pump operated by the 30 motor directly or indirectly or geared to the fly wheel. Compressed air has also been used in an independent starter attached by an automatic clutch to the motor shaft; in 35 this case an air pump on the starter supplies the air to the receiver. Several electrical methods have been tried and more of these are in use than any other form of starter. These and other devices on the 40 market have many and varied objections and disadvantages which are so well known that they need not be reiterated here.

Now I have devised a simple and effective machine that fills the dual part of starter 45 and air compressor in so far that it can instantly be converted from starter to compressor or vice versa by the movement of a lever, so doing away with a separate air pump and other complicated gear.

50 My combined machine consists of a small and compact three cylinder engine having the cylinders placed preferably at an angle of 120 deg. and operating on one crank. Each cylinder is provided with two valves 55 which operate automatically when the machine is working as an air compressor.

When working as a motor these valves are actuated mechanically by a device brought into operation by the driver.

The machine is placed preferably in front 60 of the radiator and supported from the main frame of the motor car chassis and is connected by means of a clutch which can be engaged at will with a disk on the starting handle shaft. The air receiver may be 65 placed in any suitable position on the car, while the valves and clutch may be arranged to operate by hand or foot as may be most convenient.

In order however that my invention may 70 be thoroughly understood I will now describe it, reference being made to the accompanying drawings.

Figure 1 is my starter and air compressor shown in cross section through the cylinder. 75 Fig. 2 shows it in longitudinal section with one set of valves and valve lever. Fig. 3 shows a cross section of a detail. Fig. 4 shows end elevation of disk on motor shaft with clutch on starter. Fig. 5 is a longi- 80 tudinal section showing details of clutch. Fig. 6 is a general arrangement.

A are the three cylinders set at 120 deg. to insure there being no dead center each provided with a trunk piston B having the 85 connecting rod C secured to it by the usual wrist pin D while the crank pin end of one connecting rod has a bush E the length of the pin F which is turned on the outside for the other two connecting rod ends E' E² to 90 work on so that a reduction of friction is obtained by this means. This arrangement necessitates passing the crank pin F through the one bush E and the latter through the two connecting rod ends E' E² and to do this 95 I fit one end of the crank pin into its cheek and secure it with a key and pin on the back.

Each cylinder A has its own valve chest G and valves H, H' (see Fig. 2) and when desired the two valves H, H' are mechanically driven by the cams J, J' on the main shaft K.

When the sleeve L, operated by the driver, is moved around on the shaft K as shown in Fig. 2 the mushroom headed strikers M 105 are brought into contact with the spring controlled tappets N in line with the valve spindles P. I may however attain the same end by arranging the sleeve L with strikers M, to move endwise on the shaft K. 110 The position of the tappets N and strikers M is such that no matter what position the

engine is in one of the inlet valves H , is opened when the sleeve L with striker M is brought into position and so starts the engine by admitting compressed air at the right part of the stroke in one of the three cylinders A . The sleeve L which is articulated in such a manner that it can be operated by foot or hand lever, is inclosed in suitable housing Q attached by bolts to the engine crank case. The ports R on the valve H' communicate with the open air, while the port S by the valve H connects with the pipe T leading to the air receiver T' , and the port U leads to the cylinder A .

15 The clutch, Figs. 4 and 5, connecting the starter with the motor is of the ordinary well known type and it is only necessary to add that the portion V is keyed to the starting handle shaft V' and the cone W is operated from a suitable lever by the driver's hand or foot.

16 I will now describe the working of my invention it being understood to be connected up with an air receiver full of compressed air, the stop valve on the receiver being opened and the car motor being ready to start.

17 The driver would put in gear the clutch connecting the starter with the motor and move the sleeve around (from the position shown in Fig. 3) until one of the valves H is opened (see Fig. 2) allowing the compressed air to rush in and start the motor, each inlet and exhaust valve H H' being moved in turn as the cams J J' with the shaft K , revolve. The starter moves at a great speed and quickly starts the motor. The driver then releases the sleeve lever which is at once drawn to a neutral position preferably by a spring. The machine then ceases to act as a starter, and immediately becomes a compressor rapidly restoring to the receiver the air consumed in starting. It will be noted that acting as a compressor the machine has the same cylinder capacity as when in action as a starter. If by any chance the driver omits to throw out the connecting clutch the compressor continues to draw in air through the ports 40 R and valve H' while the valve H lets the compressed air into the receiver. As soon as the pressure in the receiver is restored the safety valve, provided for the purpose lifts and allows the air to escape so that no 45 damage can be done. In some cases I may wish to reduce the travel or vary the lift of the valves H , H' so that a reduced quantity of compressed air is admitted. This may be attained by moving the sleeve L and

50 wipers M to an intermediate position in order that the inclined surface of the head instead of the extreme end operates on the tappets N . When this is done the valves H , H' will not open to their fullest extent. 55 Should the driver have to make another

start shortly the starter is again instantly ready and any number of starts can be made provided the pressure in the receiver is restored from time to time as may be necessary and in the manner described.

It will of course be understood that the size of the starter will be in proportion to the size of motor to be started, though one size could be used through a large range of motor sizes by varying the working pressure, if necessary. Thus a machine having 75 2½ inch diameter cylinders could be used to start any ordinary range of motor car. It will also be understood that the power of the machine will decrease with the air pressure: 80 but it has the great advantage over other starting devices in that it can at any convenient time restore the lost pressure quickly with very little demand upon the motor and either while the latter is running free or 85 propelling the car. While operating as a compressor the starter will tend to steady the running of the motor when running free without other load. Other starters take some time to restore the lost electricity or 90 air. The usual means would be used for overcoming the increased temperature due to compression.

My invention can readily be made to run either in a clock-wise or anti-clockwise direction while by a slight modification of the valve mechanism it can be made to start either way at will.

It will be understood that the details of carrying my invention into effect may be 100 varied from that herein described and as illustrated in the accompanying drawings without affecting the essence of my invention. I may provide springs for insuring the valves H , H' returning to their seats. 105

I claim—

1. In an engine convertible for use as a motor and pump, the combination of intake and exhaust valves, means for actuating said valves, means for disengaging said actuating means from said valves, and means carried by said actuating means for varying the throw of said valves, substantially as described.

2. In an engine convertible for use as a 115 motor and pump, the combination of intake and exhaust valves, tappets for said valves, strikers provided with inclined heads for actuating said tappets, and means for moving said strikers to disengage said tappets 120 and to vary the position of said heads with respect to said tappets so as to secure a variable throw of said valves, substantially as described.

3. In a convertible motor and pump, the 125 combination of a plurality of radially disposed engines, a common crank shaft for said engines, intake and exhaust valves for each of said engines, a tappet for each of said valves, a sleeve mounted for independ- 130

ent revolution about said crank shaft, a plurality of pairs of strikers provided with conical heads mounted for reciprocation radially in said sleeve, a pair of cams mounted on said crank shaft for continuously actuating said strikers during running of the engines, and means for rotating said sleeve to move the strikers to disengage said tappets and to vary the position of said inclined heads with respect to the tappets to vary the throw of said valves, substantially as described.

4. In a convertible motor and pump, the combination of a multi-cylinder engine having no dead center, a sleeve carried on and capable of movement on the main shaft of said multi-cylinder engine, said sleeve carrying strikers which may, by the movement of said sleeve be moved into or out of contact with and to vary the lift of the tappets for operating the inlet and exhaust valves of the engine as and for the purposes herein set forth and as illustrated in the accompanying drawings.

25 5. In a convertible motor and pump, the combination of a multi-cylinder engine having no dead center, and provided with inlet and exhaust valves arranged and controlled so that when the engine is to run as an air motor said valves are mechanically operated by cams, a sleeve capable of movement on the main shafts and carrying strikers for

operating the valves, and means for moving the said sleeve and strikers so that when driven by the engine which it has started it 35 becomes an air compressor, the action of the cams being cut off from the said valves by the movement of said sleeve and strikers, said valves being free to open and close by the suction and delivery of the air, into the 40 receiver, as and for the purposes herein set forth and as illustrated in the accompanying drawings.

6. In a convertible motor and pump, the combination of a multi-cylinder engine having no dead center, cams on the main shaft of said engine, a sleeve carried on said main shaft and capable of movement thereon, and carrying strikers for operating the valves, tappets, inlet and exhaust valves, passages 50 to the cylinders and means for actuating the said sleeve so as to cause the strikers to move into or out of alinement with the tappets and valves in combination with a clutch for coupling up to the motor to be started, as 55 and for the purposes herein set forth, and as illustrated in the accompanying drawings.

In testimony whereof, I affix my signature, in presence of two witnesses.

FREDERICK JOHN TREVALLON BARNES.
